UNITED STATES PATENT OFFICE.

EUGENE A. PATTERSON, OF DUNBAR, NEBRASKA, ASSIGNOR OF ONE-HALF
TO DIETRICK KRUSE, OF SAME PLACE.

DESIGN FOR A POST-SOCKET.

SPECIFICATION forming part of Design No. 29,550, dated October 25, 1898.

Application filed August 18, 1898. Serial No. 688,936. Term of patent 7 years.

To all whom it may concern:

Be it known that I, EUGENE A. PATTERSON, a citizen of the United States, residing at Dunbar, in the county of Otoe and State of Nebraska, have invented and produced a new and useful Design in Post-Sockets, of which the following is a specification.

This invention is a new and useful design for a post-socket, the essential feature residing in the peculiar shape of the several parts, as fully illustrated in the accompanying drawings, in which—

Figure 1 is a perspective view of the socket constructed in accordance with my design. Figs. 2 and 3 are horizontal sectional views of the socket constructed in accordance with my design.

Referring particularly to the drawings, A represents the socket proper, which is essentially rectangular in shape and has semicir-

cular openings B in the opposite sides thereof, and upon the bottom of the socket proper is an essentially rectangular-shaped boss C. The anchor portion is arranged directly below the socket proper and comprises four 25 blades or wings D, arranged at right angles to each other, as most clearly shown in Fig. 4, the edges of said blades being beveled and at their upper ends formed with round shoulders E, the lower ends tapering to a point, as 30 shown at F.

Having thus described my invention, what I claim as new, and desire to secure by Letters Patent, is—

The design for a post-socket, substantially 35 as shown and described.

EUGENE A. PATTERSON.
